UNITED STATES PATENT OFFICE.

JAMES J. HAYNES, OF CHESTNUT MOUND, TENNESSEE, ASSIGNOR OF ONE-HALF TO
E. H. KNIGHT, OF CHESTNUT MOUND, TENNESSEE.

FLAT-IRON REST.

1,285,158.

Specification of Letters Patent. Patented Nov. 19, 1918.

Application filed March 28, 1918. Serial No. 225,265.

To all whom it may concern:

Be it known that I, JAMES J. HAYNES, a citizen of the United States, residing at Chestnut Mound, in the county of Smith, 5 State of Tennessee, have invented a new and useful Flat-Iron Rest; and I do hereby declare the following to be a full, clear, and exact description of the invention, such as will enable others skilled in the art to which 10 it appertains to make and use the same.

The present invention relates to a flat iron heating attachment for open grates, and has for its object to provide a device of this character which embodies novel features of 15 construction whereby the fire in an open grate can be utilized for heating flat irons or the like, thereby avoiding the necessity of starting a separate fire for the purpose of ironing, and resulting in a saving of fuel. 20 Further objects of the invention are to provide a device of this character which can be readily fitted upon any open grate without necessitating any alterations or changes in the construction thereof, which will support 25 the flat irons in such a manner that they will be effectively heated by the fire in the grate, and which will not interfere with the usual heat and comfort to be derived from the open grate.

With these and other objects in view, the invention consists in certain novel combinations and arrangements of the parts as will more fully appear as the description proceeds, the novel features thereof being pointed 30 out in the appended claim.

For a full understanding of the invention, reference is to be had to the following description and accompanying drawings, in which:—

40 Figure 1 is a perspective view of a flat iron heating attachment constructed in accordance with the invention, showing the same as applied to an open grate.

Fig. 2 is an enlarged end view of the flat iron heating attachment.

Corresponding and like parts are referred to in the following description and indicated in all the views of the drawings by the same reference characters.

50 For the purpose of illustration the flat iron heating attachment is shown as applied to an open grate A, which may be of any conventional construction, being formed with the usual front 1 which has open spaces 55 2 therein. The attachment includes a pair

of similar and complementary end brackets 3 which have an angular formation, each of the end brackets comprising a vertical arm 3^a and a horizontal arm 3^b. The upper extremities of the vertical arms 3^a are returned 60 rearwardly to provide hook members 4 which fit over the edge of the front 1 of the grate, thereby supporting the brackets in position with the vertical arms 3^a thereof bearing against the front of the grate, while 65 the horizontal arms 3^b thereof project outwardly from the grate. These arms 3^b support the platform which consists of a series of spaced horizontal bars 5. The ends of these bars are rigidly secured in any suitable 70 manner to the horizontal arms 3^b of the end brackets, and the bars provide the platform upon which the irons 6 are placed for the purpose of heating the same. Each of the angular end brackets is provided with 75 a diagonal brace 7, the lower end of the brace being hooked around the extremity of the horizontal arm 3^b of the bracket, as indicated at 7^a, while the upper end thereof is bent around the supporting hook 4 at the 80 upper end of the bracket, as indicated at 7^b. The supporting hook 4 is thus really formed of two thicknesses of material, and this is 85 an advantage, since the supporting hook is subjected directly to the heat of the fire 90 within the open grate and might otherwise burn out in a comparatively short period of time. These diagonal braces 7 reinforce the end brackets so that a rigid construction 95 is obtained, and it will be understood that the device can be readily applied to an open 100 grate by fitting the supporting hooks 4 over the upper edge of the grate front 1. The heat from the fire in the open grate will then radiate from the openings 2 of the grate front and heat any flat irons or like members which may be placed upon the bars 5. The attachment can be used in rural or village homes where coal is used as fuel in an open grate, and will result in a great 105 saving of fuel by eliminating the necessity of building an extra fire for ironing purposes.

Having thus described the invention, what I claim as new and desire to secure by Letters Patent, is:—

The herein described flat iron heating attachment for open grates, including a pair of angular end brackets each formed with a vertical arm and a horizontal arm, the ver- 110

vertical arms having returned hooked upper ends adapted to engage the edge of a grate front, a platform connecting the horizontal arms of the brackets, and diagonal braces applied to the brackets and having the lower ends thereof hooked around the horizontal arms while the upper ends thereof are hooked and extended around the hooked upper ends of the vertical arms to fit over the same and provide a double thickness, there-

by reinforcing the supporting hooks and enabling them to resist the action of the fire.

In testimony whereof I have signed my name to this specification in the presence of two subscribing witnesses.

JAMES J. HAYNES.

Witnesses:

JAMES HUNTER,

WM. A. BLAIR.
